UNITED STATES PATENT OFFICE

CHARLES ANTON GLOCK, OF CHATHAM, ONTARIO, CANADA

DESIGN FOR A GOLF TEE HOLDING WRISTLET

Application filed August 18, 1932. Serial No. 44,626. Term of patent 7 years.

To all whom it may concern:

Be it known that I, CHARLES ANTON GLOCK, a naturalized citizen of the United States of America, and a resident of the city of Chatham, in the county of Kent, in the Province of Ontario, Canada, have invented a new, original, and ornamental Design for a Golf Tee Holding Wristlet, of which the following is a specification, reference being had to the accompanying drawing, forming part thereof.

Fig. 1 is a plan view of a golf tee holding wristlet showing my new design; and

Fig. 2 is an edge view of the same.

I claim:

The ornamental design for a golf tee holding wristlet, substantially as shown.

CHARLES ANTON GLOCK.
